UNITED STATES PATENT OFFICE.

JOHN B. UNDERWOOD, OF GRASS VALLEY, CALIFORNIA.

POCKET TYPEWRITER.

Application filed January 6, 1928. Serial No. 244,882.

My invention relates to improvements in typewriters with folding parts; and the objects of the invention are, first, to provide a typewriter of such convenient size, that it may be placed in a small case and carried in a pocket of a person's clothing; second, to afford facilities for its ready adjustment for writing; and third, to provide that it may be made to write on any suitable flat surface, such as the page of a book or surface of a package.

One form of my invention is illustrated in the accompanying drawings, in which Figure 1 is a plan view of the entire machine, unfolded; Fig. 2, an end elevation of the machine, unfolded; Fig. 3, a plan view of fragment of the machine with obstructing parts removed to show the attachment of movable parts to the frame; Fig. 4, a vertical section of the machine on the line 4-4, Fig. 3; Fig. 5, a vertical section of the machine on the line 5-5, Fig. 1; Fig. 6, a fragmentary perspective view showing the carriage for supporting the keyboard; Fig. 7, a fragmentary perspective view taken approximately between the lines 7-7 and 5-5, Fig. 1; and Fig. 8, a fragmentary perspective view of the guide rules on the line 8-8, Fig. 1.

In its operation, my machine differs from that of the typewriter which has a movable carriage on which the sheet of paper, held in place against a roller, is carried along as the writing proceeds, in that the body portion of my machine travels across the paper, or other writing surface, when the machine is being operated. Said body portion, which includes the keyboard, type bars, ribbon mechanism, and other parts attached to frame 10, (see Fig. 1), is caused to move, as hereinafter described, across the writing surface over guide rule 11, which is held in alignment by margin rule 12. Margin rule 12 grips the edge of the paper by means of strip 13, hinged thereto and kept in contact therewith, by the weight of the machine resting upon the paper. It will be observed that the frictional contact of guide rule 11, and margin rule 12, with the surface of the paper, assist in holding the machine in alignment. As the typist faces the machine in a position for operating the keyboard, with the paper attached as described, it will be seen that the margin rule is at his left.

In order to place the machine in position to begin a line of writing, he shoves the body portion of the machine, attached to frame 10, toward his left, causing it to pass over margin rule or line space rack bar 12 until said rule has reached a position slightly to the left of frame 10 center line. (See Figs. 1 and 7.) The lower face of frame 10 consists of two parallel plane surfaces meeting in a perpendicular offset on a line 7' 7', Fig. 1, shown in detail in Fig. 7. This makes room for frame 10 to pass over margin rule 12.

Guide rule or letter space-rack bar 11 is made with offset or grooved edges so that it will slide in ways 14, frame 10. (See Figs. 4 and 5.) In the upper surface of guide rule 11, is a rack of gear teeth 15, Fig. 8. This rack engages pinion 16, (see Figs. 3 and 4), which is attached to shaft 17, said shaft carrying also ratchet wheel 18 and spiral spring 19, as shown. Spiral spring 19 is secured to shaft 17 near pinion 16, and to plate 20 which is attached to frame 10. Ratchet wheel 18 is engaged by pawl 21 and its carrying arm 22. Arm 22 may be caused to oscillate by downward movement of universal bar 23, (which movement results when a letter key is pressed as hereinafter described), and the tension of spiral spring 24 when the pressure on bar 23 is released. Now, it will be seen that when the body portion mounted on frame 10, is shoved back to the position for starting a line of writing, spring 19 is wound. In such condition spring 19 has potential energy sufficient to propel, through pinion 16 and rack 15, the body portion of the machine along rule 11 to the right margin of the paper. However, such reverse motion is controlled by means of ratchet wheel 18, ratchet arm 22, and ratchet 21, as hereinbefore described. When ratchet arm 22 is caused to oscillate, the right hand movement referred to proceeds in steps, each step corresponding to a tooth in ratchet wheel 18, the combination of parts being so proportioned that each step is of proper length for a letter space in the writing line. It is not deemed necessary to describe in detail the ratchet arm combination, for it is practically the same as that used on many machines including typewriters in particular.

The line shift, or means provided for shifting frame 10 to a new line after the line of writing has been completed, is shown

110

in a general way in Fig. 1, and in detail in Fig. 8. Margin rule 12 is held in alignment by guides 26 and 27, which are secured to guide rule 11 in such a manner as to form 5 a continuous piece. (The section lines show this but lines representing the edges of the separate pieces are shown in order to better illustrate the position of parts.) On the inner edge of margin rule 12 is a rack of 10 gear teeth 28', which engage the lower portion of wheel 28. Wheel 28 is a combination ratchet pinion having an upper portion provided with ratchet teeth and a lower portion with cogs or teeth designed to engage 15 those of rack 28'. Both the cogs and the ratchet teeth are so designed with blunted tips as to rotate as a journal in circular cavity 29. This wheel is held in place by screw 30, the head of which also acts as a 20 journal, as shown in Fig. 8. Dog 31 fitted to slide in slot 32 and held in place by spring 33, also engages the teeth of rack 28' as shown. It is intended that spring 33 shall be of such strength as to hold rule 12 in 25 place and at the same time elastic enough to permit said rule, with its guides, to move along margin rule 11, if greater force is applied than that required to keep the machine in alignment when writing. Dog 31 may 30 be pressed against spring 33, and shoved over until its hooked portion engages the hooked portion of slot 32. In this position it is held away from engaging rack 28', thus 35 permitting margin rule 12 to be easily slid or removed. The rotation of wheel 28, which causes guide rule 11 to travel along margin rule 12, is effected by its ratchet portion which engages dog 34, (shown only in Fig. 7) when frame 10 is shoved back over 40 margin rule 12, hereinbefore described. The degree of rotation that wheel 28 will undergo, before the motion of frame 10 is arrested by obstruction 7' 7", will depend upon the position of dog 34. Dog 34 is secured to the 45 lower end of shaft 35. (See Fig. 5.) At the upper end of shaft 35, pointer 36 is secured. (See also Fig. 1.) Pointer 36 may be placed in any one of three positions, which through connection with shaft 35, 50 make it possible to easily place dog 34 in a corresponding position. If dog 34 is placed in the position shown in Fig. 7, it will engage wheel 28 early enough in the movement, cause its rotation of sufficient degree, 55 to propel rule 11, carrying frame 10, down the writing page a distance of three lines of writing. But, if dog 34 is placed in the position indicated by the dotted lines, it will effect only sufficient motion to propel 60 rule 11 down the writing page a distance of two writing lines. The two line space is effected by an intermediate position of the pointer. In case it is desired to shift to a new line when the machine is writing near 65 the center of the page, guide rule 12 may

be pressed firmly against the surface of the writing page by one hand, and frame 10 forced up or down the page with the other. If the machine happens to be in a position in which wheel 28 is exposed to view, as in 70 Fig. 1, said wheel may be rotated by means of the thumb or by use of a suitable wrench.

At this point it is convenient to call attention to strip 13, attached by hinges 37 to the lower surface of rule 12. (See Figs. 7 75 and 8.) This is a very thin strip, which with rule 12 forms a pair of jaws to secure the paper firmly. When the machine has reached the limit of rule 12, the writing page carrying the machine may be slid over 80 on the table or desk top, upon which it is placed, until rule 12 projects over the edge. Strip 13, being thus released, drops open. While the operator holds the machine firmly in place with one hand, he may slide rule 85 12 further down the page with the other, disengaging dog 31 if necessary. The machine may then be brought back on the table, and the writing proceeded with as before. While this convenience requires only a short 90 margin rule, the margin rule may be made long as the machine, since it may be easily removed when the machine is placed away in its case. When it is desired to use the machine for writing on a package, or for 95 writing in a book, guide rule 12 may be held in place by the hand or by thumb tacks.

I will now describe the operation of the keys, type bars, ribbon shift, and other mechanism, making up the body portion of 100 the machine and secured to frame 10. A number of type bars 38 38', arranged radially on the arc of a circle, each carrying at its outer end a suitable piece of type, are made to hinge on shafts 39 and 40, (see Figs. 105 1, 3, and 5) so that each of said type bars may be caused to impress its attached type upon an inked ribbon against the writing surface at a point X, numbered 41, said point being the center of a circle whose arc 110 was referred to. Said type bars are operated through intermediate bars 42, by key bars 43 44, to which are attached keys labeled with letters of the alphabet and other characters, as shown. It will be seen 115 that the arrangement which provides an individual type bar for each character desired, makes it possible for the machine to write on a flat surface, thus satisfying an object of the machine. Reference to Fig. 2, 120 will disclose the compact arrangement of parts, a feature which satisfies another object of the invention. In order to facilitate compactness, the type bars are so arranged 125 that the type rests in two rows on the arc shaped shelf 45, as shown in Figs. 1 and 5. This arrangement permits the type pieces to lie closely adjacent to one another, but requires two styles of type bars, each style having a separate shaft in order that the 130

type may be caused to strike the paper at a common point. Fig. 5, shows these two kinds of type bars and their connections with other parts. Type bar 38, hinges on the upper shaft 39, while type bar 38', hooks over shaft 39 and hinges on shaft 40. Bosses 41, secured to frame 10, serve as supports for shaft 40 and as guides for type bars 38'. Type bars 38', thus aligned, serve as guides for type bars 38.

It will be observed that type bars 38 38' terminate at the shaft end in the form of pinions or cog wheels, the teeth of which engage teeth at the ends of intermediate bars 42, which hinge on shaft 46 as shown. Bars 46 are held in alignment by guides 47, attached to frame 10. Said bars tend to swing on shaft 46 in a clockwise direction because of springs 47 attached to shafts 48 and 49, as shown. If one of the intermediate bars 42 is caused to swing on its shaft 46 against the tension of its attached spring 47, it will cause its engaged type bar 38 or 38' to swing on its shaft until the type of said bar strikes the inked ribbon on the paper in a position shown by the dotted lines. If now the force tending to swing intermediate bar 46 in an anticlockwise direction is released, spring 47 will draw said intermediate bar back to its previous position of rest on shelf 45.

By reference to Figs. 2 and 5, it will be seen that each key bar 43 44, is made to operate any one of three intermediate bars, depending on its longitudinal position as effected by the position of carriage 50 51 (Fig. 6), to which all key bars are attached, the position of which carriage is controlled by shift keys 52 and their related mechanism, as shown in Fig. 2. Figs. 2 and 5, show how bosses attached to the key bars engage the suitably hooked ends of intermediate bars 42. If carriage 50 51, is forced outward it will cause key bars 43 44 to disengage one set of intermediate bars and to engage a different set of intermediate bars; or if it is forced in the opposite direction it will cause said key bars to engage another set of intermediate bars. The manner in which intermediate bars 42 engage key bars 43 44 laterally, is shown in Fig. 1 by the breaking away of the characters Y7, and H?, of the key labels. The hooked end of an intermediate bar 42 is also clearly shown by the one intermediate bar in Fig. 3.

The form of carriage 50 51 is shown in Fig. 6. It is really a combination of two carriages, one being carriage 50, attached to frame 10 through slot 57 by means of screw 58, and the other, sub-carriage 51, being attached to carriage 50 through slot 59 by means of screw 60. It may be seen that this arrangement permits carriage 50, carrying sub-carriage 51, to be moved in and out on frame 10 to the limit of slots 57. This movement may be arrested at any one of

three points, by means of shifting mechanism shown best in Figs. 1 and 2. Two sets of parts, 53, 55, 56, etc., are shown attached to a common shaft 54', so that the operation of similar devices attached to said shaft is simultaneous. If one of the shift keys labeled FIG is pressed down, arm 53 carrying dog 55 and spring 56, is brought over to the position shown by the dotted lines in Fig. 2. During this operation the free end 75 of dog 55, which is attached at its outer end to carriage 50 by means of pin 50', and at its free end to arm 53 by means of a pin through a slot, as shown, is caused to raise against spring 56 and disengage the center 80 slot of boss 54 (which serves also to support the journal of shaft 54') and to engage the last notch of said boss. The carriage is then in position to engage a set of intermediate bars as previously explained. Carriage 50 51 85 may be brought back to the position previously occupied, by pressing one of the shift keys labeled CAP, or it may be brought further over to a new position, by more pressure applied to one of said CAP shift 90 keys. In the latter position, the key bars will engage a different set of intermediate bars; and in any one of the three positions, carriage 50 51 will be held secure. This is clearly shown in Fig. 2.

Attention has been called to the fact that carriage 50 also carries sub-carriage 51, and that sub-carriage 51 supports the outer row of key bars which correspond to the keys labeled Z, X, C, V, B, N, M, Comma, and &, 100 with other shift characters. When it is desired to place the machine away in its case, sub-carriage 51 containing said keys, may be shoved in so that the keys will occupy a space within the area of frame 10. When 105 this movement is effected, guides 44' on key bars 44 engage the hooked ends of the related intermediate bars 42, and are thus held secure. At this point we may call attention to fin 61, shown only in Fig. 5. This fin 110 is slotted to receive and guide intermediate bars 42, and also key bars 43. By means of studs 52 properly located with reference to fin 61, the key bars are prevented from moving when carriage 50 is not in one of its 115 three positions to secure proper contact between the key bars and intermediate bars.

The device for spacing between words, or when otherwise desired, is shown in Figs. 1, 2, 3, and 4. Elongated key 62 is secured 120 to bars 63, which pass over bar 23 and loop over and under shaft 54', as shown in Fig. 4. When said key is pressed down it also forces bar 23 down, setting off ratchet 22 and causing the machine to take a letter space as 125 hereinbefore described. When it is desired to place the machine away in its case, the space bar may be shoved in over frame 10 in a manner similar to that described for carriage 51.

The characters are impressed on the paper or other writing surface, by means of an inked ribbon commonly used on typewriters in general. The ribbon arrangement is shown clearly in Figs. 1 and 3. Spools 64, carrying ribbon 65, rotate freely on shafts 66 unless thumb nut 66' is tightened down against the spool, in which case that spool will be secured to its shaft. The ribbon 10 passes over plate guide 67 through its guards, as shown. This guide is swung by hinges 67' to T bar 68, the center arm of which fits and slides in ways 69 of frame 10. Hinged to the ends of each side arm of T bar 68, are bars 70, each containing a rack of ratchet teeth which engage ratchet wheels 71 attached to spool shafts 66, as shown in Fig. 3. Ratchet wheel 71 is prevented from turning in a reverse direction by pawl 72, as shown. Bar 70 is held up to ratchet wheel 71 by springs 70'. It will be seen, that if T bar 68 is caused to undergo the reciprocating motion described, bars 70 will also undergo a reciprocating motion, and that this motion 25 will cause ratchet wheels 71, with shafts 66, to rotate. If one of the ribbon carrying spools is held fast to its shaft by the thumb nut provided, while the other spool is allowed to play freely on its shaft, ribbon 65 will be 30 wound on the spool held secure and unwound from the one which is loose. This tight and loose spool feature is not new, for it is to be found on other machines including typewriters.

35 Ribbon guide plate 67 is held flat against the writing surface by means of slide 75, Fig. 4, which is secured to T bar 68 by screw 76 through slot 77. Slide 75 has a grooved boss 78 which engages the end of bar 73, which bar swings near its center on pin 73'. The upper end of this bar is attached by means of a pin to the end of bent bar 74, having a notch 74' near the bowed section of its other end, which notch engages 45 a tooth at the upper end of arm 22. Bar 74 continues further, terminating in an inclined plane portion which may engage part of carriage 51 when said carriage is shoved in as hereinbefore described. As arm 22 is caused to oscillate by the downward movement of bar 23 and spring 24, as hereinbefore described, bar 74 is caused to undergo a reciprocating motion; in turn transmitting an oscillatory motion to bar 73 on journal 73'. 50 This in turn transmits, through grooved slide 75 reciprocating motion to T bar 68 forcing it in and out under the striking type, whose action it will be recalled, is also controlled by arm 22. Both actions are synchronous with the movement of a pressed key.

By referring to Fig. 1, it will be seen that when carriage 51 is slid in, that it lifts the end of bar 74 until arm 22 is disengaged, 65 and then shoves said bar until bar 73 is

turned on its axis to the position shown by the dotted lines. This movement is the same as that described for the ribbon shift except that it is of greater magnitude, and the force is sufficient to cause a movement of slide 75 70 on T bar 68, when the T bar has reached its limit of movement defined by ways 69 of frame 10. As slide 75 moves along T bar 68, that portion resting upon ribbon guide 67 at 75', is removed from contact with the 75 ribbon guide, which now tends to hinge upward because of ribbon tension. As a further aid to this swinging movement of guide 67, link 76, attached to slide 75 and to guide 67, becomes taut. When the movement is 80 complete, guide 75 stands in the position of a plane perpendicular to that of the lower surface of frame 10. This is shown by dotted lines. With parts thus folded in, and with margin rule 12 removed as hereinbefore described, the machine may now be placed in a small box or carrying case. It is evident that it may be unfolded again by simply pulling out the parts which were 85 folded in. 90

Having thus fully described my invention, what I claim as new, and desire to secure by Letters Patent, is—

1. The combination in a typewriter, having a movable body portion provided with 95 a writing mechanism, of a guide rule having a rack of teeth exposed on its upper surface, its lower surface making frictional contact with the writing surface, said rule providing a complete supporting track for the 100 movable body portion, said body portion having ways to receive said guide rule, a pinion to receive said rack, a shaft carrying said pinion and supported in said body portion, substantially as described. 105

2. The combination in a typewriter, having a movable body portion of a guide rule having a rack of teeth, the movable body portion having ways to receive said guide rule and a pinion to receive said rack, said 110 pinion being secured or journaled to a shaft and having secured thereto and to said body portion a spring, said spring being the means of transmitting energy to rotate said pinion to propel said body portion 115 across the writing surface in the direction of the writing, substantially as described.

3. The combination, in a typewriter of the character described, of a guide rule having perpendicular ways, a ratchet pinion secured thereto, the guide rule also having a slot and a dog fitted therein, with a margin rule, held in alignment by said perpendicular ways, and having a rack to receive said pinion and said dog. 120

4. The combination, in a typewriter of the character described, of a margin rule with a strip or plate hinged thereto and facing against the lower surface of said margin rule, said strip being held in place against 130

a sheet of paper by the weight of said margin rule resting on said sheet of paper.

5. The combination, in a typewriter of the character described, of a guide rule having perpendicular ways, a margin rule communicating with and held in alignment by said ways, with a body portion having its lower contact surface provided with ways communicating with said guide rule, said 10 body portion having a recess to receive said margin rule, in the manner described.

6. The combination, in a typewriter of the character described, of a guide rule having perpendicular ways, a ratchet pinion secured thereto, with a margin rule held in alignment by said perpendicular ways, and having a rack to receive said ratchet pinion, and with a body portion having an adjustable dog communicating with said ratchet 20 pinion, in the manner described.

7. In a device of the character described, a number of straight type bars, each terminating in a pinion, a circular shaft, on which the straight type bars are hinged, a number of bent type bars provided with cogs shaped so as to clear the circular shaft hing- 25

ing said straight type bars, a second circular shaft on which the bent type bars are hinged, the two circular shafts being placed parallel to each other, so that type attached to said 30 type bars shall lie closely in two adjacent circular paths, with the cogs of the straight type bars above the cogs of the bent type bars, gear means for selectively actuating said cogs, both sets of type bars communicating 35 their free ends to a common striking point, as shown.

8. In a device of the character described, a body portion having mounted thereon, a movable bar, a shaft, a ratchet wheel secured 40 to the shaft, said shaft carrying also a pinion, a spring secured to said shaft and to said body portion, a ratchet arm and a ratchet to control the movement of said ratchet wheel, and operated by said movable bar, 45 a shiftable ribbon guide, linked bars connecting said ribbon guide and said ratchet arm, a shift key operatively connected to said movable bar, and a means of folding in said shift key. 50

In testimony whereof I affix my signature.
JOHN B. UNDERWOOD.
